UNITED STATES PATENT OFFICE.

WILLIAM HENRY STIMPSON, OF WINTHROP, AND FRANK ALLEN BRADFORD, OF DORCHESTER, MASSACHUSETTS, ASSIGNEES TO MILFORD IRON FOUNDRY, OF MILFORD, MASSACHUSETTS, A CORPORATION OF MASSACHUSETTS.

LEATHER-WORKING MACHINE.

No. 904,160.

Specification of Letters Patent.

Patented Nov. 17, 1908.

Application filed January 17, 1908. Serial No. 411,270.

To all whom it may concern:

Be it known that we, WILLIAM HENRY STIMPSON, of Winthrop, county of Suffolk, and State of Massachusetts, and FRANK ALLEN BRADFORD, of Dorchester, in the county of Suffolk and State of Massachusetts, have invented certain new and useful Improvements in Leather-Working Machines, of which the following is a specification.

10 This invention relates to machines for treating the surfaces of sheets of leather by applying a rotary operating member to a sheet which is yieldingly supported by a bed, the operating member being adapted to 15 rub, brush or otherwise treat the exposed surface of the sheet.

The invention has particular reference to a machine for setting and scouring leather by the action of a rotary tool or operating 20 member, which is located in the center of a working space formed between the end portions of the supporting frame of the machine and a bed which is also located at the central portion of the working space, in position to coöperate with the rotary working 25 member, the arrangement being such that there is sufficient vacancy in the working space at each end of the operating member and bed for the accommodation of portions 30 of the leather sheet which are not in contact with said parts, but projects theréfrom, as is the case when the width or length of the leather sheet is considerably greater than that of the operating member and bed.

35 The invention has for its object to provide a machine of this character, with a plurality of interchangeable operating members so mounted that either member can be readily displaced from its operative position adjacent to the bed, and another member substituted for it, the displaced member occupying a portion of one end of the working space, where it is out of the way and inclosed by a shield, and at the same time is 40 readily accessible, and adapted to be returned to its operative position.

To this end the invention consists in the improvements which we will now proceed to describe and claim.

50 The accompanying drawing, forming a part of this specification, represents a perspective view of a leather working machine embodying our invention.

The supporting frame of the machine in-

cludes two end portions 12 12 and suitable 55 connections between said end portions, the whole forming an elongated working space between the end portions 12, which space contains the rotary working members and the bed hereinafter described. 60

13 represents a bed which is yieldingly supported at the central portion of said space, and occupies only a portion of the length of the working space, so that spaces 65 are provided between the ends of the bed 13 and the end portions 12 of the frame, for the reception of portions of a sheet of leather which may project from either direction from the ends of the bed. The bed 13 is yieldingly connected with a fixed cross bar 70 on the supporting frame as is common in leather scouring machines. The bed is adapted to be pressed yieldingly toward the rotary operating member by means of a treadle 16, pivoted to a fixed support, and a 75 connecting rod 18 connecting the treadle with an ear on the bed 13.

19 represents a shaft which is journaled in bearings 20 in the end portions 12 of the frame, said shaft extending through the 80 working space between said end portions, and being driven by any suitable means, such as a belt running on a suitable pulley affixed to the shaft.

21 represents a rotary operating member, 85 mounted on the shaft 19, and rotated thereby, said member being adapted to act on a sheet of leather supported by the bed 13. The operating member 21 may be of any suitable construction, and adapted to perform various operations, such as setting, 90 scouring and brushing, the member being of practically cylindrical form, and provided with suitable working material on its periphery. The length of the working member 21 is preferably substantially equal to that 95 of the bed 13, so that, like the bed, its ends are separated from the ends of the working space sufficiently to permit portions of the sheet of leather to project from the ends of 100 the working member.

A machine embodying the construction thus far described, the working member 21 being rigidly affixed to the shaft 19, and not capable of endwise movement thereon, is 105 common and well known, and is not claimed herein.

In carrying out our present invention, we

provide a plurality of working members 21, two members being preferably employed, each member being connected with the shaft 19 in such manner that the members are 5 adapted to slide lengthwise upon the shaft, while at all times rotatively engaged therewith. We have here shown two rotary working members 21, one of which is provided with bristles or brush material, 10 ranged in strips or sections, and rigid rubbing blades alternating with the strips of brush material. The other rotary working member is provided with rigid rubbing blades, which are not accompanied by brush material. The two members are, therefore, 15 adapted to perform different operations on a sheet of leather.

The shaft 19 is provided with a longitudinal coupling member, which is preferably a 20 keyway or slot 26, and the hub of each rotary working member is provided with a complementary coupling member, preferably a key, adapted to slide endwise in the keyway 26, said key and keyway providing a 25 rotative and a sliding connection between the shaft and the working members, so that each member can be moved into one of the end portions of the working space, and thus separated from the bed 13, the other working member being at the same time moved 30 into position to coöperate with the bed. Suitable means are provided for securing the operating members rigidly to the shaft in any position, so that they may be prevented 35 from endwise movement when such movement is not desirable.

29 29 represent shields, which are supported by the end portions of the frame in position to prevent contact between the rotary member, which is displaced from its 40 operative position, and portions of the leather sheet which project under the displaced member. The shields are preferably strips of sheet metal formed and supported 45 as shown in the drawing.

It will be seen that by the employment of a plurality of interchangeable rotary

working members, we are enabled to use the same machine for performing different operations on a sheet of leather without actually removing any part from the machine, and substituting another part therefor, the operation of interchanging the working members being effected by simply sliding said members along the shaft 19.

It is obvious that our invention is not limited to any particular formation or structure of the interchangeable operating members, and that the details of mechanism for supporting and rotating said interchangeable members may be variously modified without departing from the spirit of the invention.

We claim:—

1. In a machine of the character stated, 65 an elongated driving shaft, a plurality of interchangeable working members each rotatively engaged with the shaft and slidably endwise thereon, a supporting bed for the material to be operated upon when either 70 of said working members is in operative position on the shaft, and shields for said working members when out of operative position on the shaft.

2. A machine of the character stated, 75 comprising a supporting frame having end portions separated by a working space, a bed occupying a part of said space midway between said end portions beneath and adjacent to said shaft, a plurality of individual 80 operating members independently rotatively supported and movable endwise one at a time in said space, and shields supported by the frame at the end portions of the working space each adapted to coöperate 85 with one of said members when the same is in an inoperative position.

In testimony whereof we have affixed our signatures, in presence of two witnesses.

WILLIAM HENRY STIMPSON.
FRANK ALLEN BRADFORD.
